DRAFT REGULATOR

Floyd R. Hoaglin, Lansing, Mich., assignor to
 Motor Wheel Corporation, Lansing, Mich., a
 corporation of Michigan

Application July 2, 1945, Serial No. 602,701

7 Claims. (Cl. 236—45)

1

This invention relates to improvements in draft regulators for combustion apparatus.

The principal object of the invention is to provide a draft regulator of especially economical construction.

Another object of the invention is to provide a draft regulator comprising a frame and damper blade which can be formed from a single blank of sheet metal.

A still further object is to provide a draft regulator in which the pivot bearings for the damper blade pivot shafts as well as the stop means for limiting the movement of the damper blade can be formed from a single blank of sheet metal.

Another object is to provide a pivot bearing and stop bracket that can be quickly and easily attached to the frame of the draft regulator.

These objects will more fully appear in the following specification when read in connection with the accompanying drawings, wherein:

Figure 1 is a front elevational view of a draft regulator embodying the invention;

Figure 2 is a cross-sectional view taken on substantially the line 2—2 of Figure 1;

Figure 3 is a fragmentary front elevational view on an enlarged scale of a portion of the draft regulator shown in Figure 1;

Figure 4 is a fragmentary side elevational view of the portion of the regulator shown in Figure 3; and

Figure 5 is a fragmentary cross-sectional view taken on substantially the line 5—5 of Figure 3.

The draft regulator in general comprises a damper blade 10, an annular frame 11, and a balance weight assembly 12. It is attached to the open end of a collar 9 secured to a flue outlet not shown. The damper blade 10 and frame 11 are pressed from sheet metal. The balance weight assembly 12 is preferably of the type disclosed in the John W. Miller et al. Patent No. 2,453,096, granted November 2, 1948.

The damper blade 10 is a circular sheet metal member and the frame 11 is an annular ring. Both blade and frame are formed from a single blank of sheet metal, in order to conserve material, the damper blade being punched from the central part of the blank.

The peripheral portion of the damper blade is substantially flat. However somewhat above the center of the blade the metal is slit at 13. The portion between the center and radially outer slit is pressed rearwardly, while the portion between the center and radially inner slits is pressed forwardly to form pockets to receive a pair of pivot shafts 14. The pivot shafts extend beyond

2

the rim of the blade and are pivoted on the frame 11 as will more fully appear presently.

The blade is provided with a forwardly pressed recess 15 above the pivot axis. In the center of the recess is an aperture to receive the balance weight assembly 12.

The balance weight assembly comprises a hub 16, a shaft 17, a weight 18 and a knob 19. The hub has a bearing therein to rotatably receive the shaft 17. The bearing is provided with a helical groove 20 which cooperates with a spring pressed button 21 in the shaft whereby rotation of the shaft causes an axial movement of the weight 18, shaft 17 and knob 19. This movement changes the center of gravity of the entire assembly and varies the resistance of the blade to swinging about its pivot. This effect is well known and need not be further described.

The frame 11, as above mentioned, is formed from the same sheet metal blank from which the blade 10 is pressed. The frame is an annulus of generally Z-shaped cross-section. It has an outer flange 22 which abuts the end of collar 9, a cylindrical portion 23 which telescopes within the collar 9, and a radial flange 24 within which the damper blade is hung. The flange 24 is pressed rearwardly at two places to form recesses 25, the purpose of which will appear presently. Substantially centrally of the recesses 25 slots 26 are cut.

Two one piece brackets 27 are attached to the frame to provide pivot shaft bearings and stops for limiting the pivotal movement of the damper blade. The brackets are stamped from sheet metal. They are similar in shape but reversed from each other. Each bracket has a bearing portion 28 and a pair of stop portions 29 and 30 at right angles to the bearing portion. Bearing portions 28 are provided with oval bearing apertures 31 therein. Attaching lugs 32 are formed on one corner of each bearing portion.

Stop portions 29 and 30 are formed to the configuration shown in Figure 3. Stop portions 29 are offset forwardly from the stop portions 30 as shown in Figure 4. The upper edges of stop portions 29 are located slightly above the bearing apertures 31.

The two brackets are attached to the frame by tilting the lower ends thereof away from the frame, inserting the lugs 32 in the slots 26, and then swinging the lower ends of the brackets into contact with the frame. They are then attached permanently to the frame by rivets 33 inserted in openings previously formed in the brackets and frame. Of course before permanently attaching both brackets to the frame, the bearing shafts

on the damper blade are inserted in the bearing apertures 31. Then when the brackets are riveted to the frame the entire assembly of damper blade, frame, and brackets are held in proper relationship to each other.

The centers of the oval bearing apertures 31 are located in the plane of the flange 24 on the frame. This is permitted by the recesses 25 which are formed in the frame. Also the oval shape of the bearing apertures reduce friction between the shafts 14 and bearing surfaces, because the shafts can roll on the lower edges of the apertures 31 instead of the usual rotating and sliding motion characteristic of cylindrical bearings.

The operation of draft regulators of this character are well known and need not be described in detail. Suffice it to say that as the area of the part of the blade 10 below the pivot axis is greater than the area of the part above the axis, any difference in pressure between the air inside of the flue and the air outside thereof causes a tendency for the damper blade to swing on its axis. If the air pressure inside the flue is lower than that outside, the lower part of the damper swings inward to admit more air to the flue. Variations in that pressure difference, normally spoken of as draft, causes the damper blade to open and close, maintaining a constant draft. The draft may be regulated by adjusting the weight toward and away from the plane of the blade.

The upper edge of stop 29 limits inward movement of the lower part of the damper blade, because when the blade swings through slightly less than 90° from its vertical position it contacts stop 29. Stop 30 prevents any movement in the opposite direction of the damper from its vertical position, which might be occasioned by a down-draft in the flue.

From the foregoing it will be seen that the present invention provides a very simple, economical, and easily fabricated draft regulator. There is little wasted material, the only waste occurring in forming the brackets 27 and the blank from which the frame and damper blade are formed. Furthermore, the one piece brackets 27 require little material themselves and are very easily assembled.

The scope of the invention is indicated in the appended claims.

I claim:

1. A draft regulator comprising a frame having a substantially plane portion with an opening therein, said plane portion having a pair of apertures therein on opposite sides of said opening, a damper blade substantially filling said opening, means pivotally connecting said damper blade to said frame comprising journal means on said blade, a pair of brackets, each of said brackets having a bearing portion at right angles to said blade and receiving said journal means, said brackets having integral tongues inserted in said apertures for attaching said brackets to said frame, said brackets also having stop means thereon engageable with said blade for limiting the pivotal movement thereof in both directions.

2. A draft regulator comprising a frame having a substantially plane annular portion with an opening therein for the reception of a damper blade, said plane portion having axially opening recesses therein on opposite sides of said opening and apertures in the bottoms of said recesses, a damper blade in said opening, and means for pivotally mounting said damper blade in said frame

comprising a pair of one piece brackets having bearing flanges at right angles to the plane of the frame and received in said apertures, said bearing flanges having shoulders thereon engaging axially opposite sides of said frame, said brackets having stop means thereon parallel to the plane of the frame and engageable with the blade for limiting the pivotal movement of the damper blade in both directions.

3. A draft regulator comprising a frame having a substantially plane portion with an opening therein, a damper blade substantially filling said opening when said blade is in closed position, means pivotally connecting said damper blade to said frame comprising journal means on said blade, and a pair of brackets attached to said frame, each of said brackets having a bearing flange receiving said journal means, each of said brackets having stop means thereon engageable with said blade, said stop means comprising a generally Z-shaped section of said bracket having one leg of said Z-shaped section parallel to, and attached to, the plane portion of said frame and overlapping said blade at one side of said journal means, for limiting the movement of said blade in one direction, the other leg of said Z-shaped portion overlapping said blade in the region of said journal means and spaced from said blade, when the blade is in the plane of said plane portion, for limiting movement of the blade in the opposite direction.

4. A draft regulator comprising a frame having a substantially plane annular portion with an opening therein for the reception of a damper blade, a damper blade in said opening, said frame having a pair of apertures therein for the reception of bearing brackets, and means for pivotally mounting said damper blade in said frame comprising a pair of one piece brackets having bearing flanges at right angles to the plane of the frame and received in said apertures, said bearing flanges having shoulders thereon engaging axially opposite sides of said frame, said brackets having stop means thereon parallel to the plane of the annular portion of the frame and engageable with the blade for limiting the pivotal movement of the damper blade in both directions.

5. A draft regulator comprising a frame having a substantially plane annular portion with an opening therein for the reception of a damper blade, a damper blade in said opening, said frame having a pair of apertures therein for the reception of bearing brackets, and means for pivotally mounting said damper blade in said frame comprising a pair of one piece brackets having bearing flanges at right angles to the plane of the frame and received in said apertures, said bearing flanges having shoulders thereon engaging axially opposite sides of said frame, said brackets having stop means parallel to the plane portion of the frame extending from said flanges in a direction circumferentially of the frame and fixedly secured thereto.

6. A draft regulator comprising a frame having a substantially plane portion with an opening therein, said plane portion having a pair of apertures therein on opposite sides of said opening, a damper blade substantially filling said opening, said blade being substantially in the plane of said plane portion when closing said opening, and means pivotally connecting said damper blade to said frame comprising journal means on said blade and a pair of brackets, each of said brackets having a bearing portion at right angles to said blade and receiving said journal

means, said brackets having integral shouldered tongues inserted in said apertures for attaching said brackets to said frame, the shoulders on said tongues being positioned on one side of said plane portion and the bearing portion on the opposite side of said plane portion of the frame.

7. A draft regulator comprising a frame having a substantially plane annular portion with an opening therein for the reception of a damper blade, a damper blade in said opening, the plane portion of said frame having a pair of apertures therein for the reception of bearing brackets, and means for pivotally mounting said damper blade in the plane annular portion of said frame comprising a pair of one piece brackets having bearing flanges at right angles to the plane of the frame and received in said apertures, said bear-

ing flanges having shoulders thereon engaging one side of the plane annular portion of said frame adjacent said apertures and each of said brackets having leg portions overlapping and secured to the other side of the plane annular portion of said frame.
